UNITED STATES PATENT OFFICE.

HERBERT H. ICE, OF AUGUSTA, KANSAS.

PUMPING-POWER.

1,288,008.

Specification of Letters Patent. Patented Dec. 17, 1918.

Application filed October 15, 1917. Serial No. 196,715.

To all whom it may concern:

Be it known that I, HERBERT H. ICE, a citizen of the United States of America, residing at Augusta, in the county of Butler 5 and State of Kansas, have invented certain new and useful Improvements in Pumping-Power, of which the following is a specification, reference being had therein to the accompanying drawing.

10 This invention relates to a power mechanism particularly adapted for operating oil wells and other pumps and has for its object the improvement of the construction of the hub of a band wheel power having several motions, as compared to the ordinary power having a single motion.

Another object of this invention is the provision of a simple and efficient trammel disk whereby the reciprocating rod may be 20 effectually operated through the rotation of the band wheel.

The present invention is an improvement upon my previous patent bearing Number 859,451 issued July 9, 1907.

25 Other objects and advantages of the present invention will appear throughout the following specification and claims.

In the drawings;—

Figure 1 is a top plan view of the apparatus;

Fig. 2 is a central longitudinal section through the band wheel and support therefor;

Fig. 3 is a top plan view of the trammel disk, the reciprocating rod being removed therefrom;

Fig. 4 is a section taken on the line 4—4 of Fig. 2;

Fig. 5 is a section taken on the line 5—5 of Fig. 2;

Fig. 6 is a bottom plan view of the reciprocating rod and disk which is adapted to coöperate with the trammel disk;

Fig. 7 is a section taken on the line 7—7 of Fig. 6;

Fig. 8 is a vertical section through one of the trammel disk shoes and cup supported thereby;

Fig. 9 is a side elevation of the outer end 50 of the reciprocating rod showing the sliding shoe and support coöperating therewith;

Fig. 10 is a vertical section through the structure shown in Fig. 9;

55 Fig. 11 is a section taken on the line 11—11 of Fig. 1;

Fig. 12 is a top plan view of one of the cup carrying plates adapted to be supported upon the disk carried by the reciprocating rod;

Fig. 13 is a section taken on line 13—13 of Fig. 5;

Fig. 14 is a bottom plan view of the reciprocating shoe shown in Fig. 3;

Fig. 15 is a perspective view of one of the side plates carried by the reciprocating shoe;

Fig. 16 is a detailed perspective view of the end sockets carried by one of the reciprocating shoes.

By referring to the drawings it will be seen that 1 designates the base which may be of any suitable or convenient structure or constructed out of any suitable or convenient material and by carefully considering Fig. 2 it will be seen that a base plate 2 is mounted upon the base 1 and is provided with a depending cup portion 3 which is embedded within the base 1. Suitable anchoring rods 4 are also employed and are embedded within the base 1 and engage the radiating ribs 5 of the base plate 2 as illustrated clearly in Figs. 4 and 5 of the drawings. The base 1 is provided with an upwardly extending standard 6 over which standard fits the supporting shaft or pintle 7.

This supporting shaft or pintle 7 is provided with a threaded upper end 8 over which threaded upper end 8 fits a bearing collar 9. This bearing collar 9 is provided with a pocket portion 10 upon the under-

90 face thereof to constitute an oil receptacle or reservoir for freely lubricating the bearing portions of the apparatus. This bearing collar 9 has its side portions 11 inclined inwardly toward the lower ends thereof for the purpose of fitting snugly within the hub plate 12 of the band wheel 13. A suitable oil port 14 is formed in the operating collar 9 for the purpose of permitting lubricant to pass into the pocket 10 and the upper face of the bearing collar 9 is provided with a plurality of circumferentially extending oil channels 15 for the purpose of permitting oil to be maintained upon the upper face of the bearing collar 9.

105 This bearing collar 9 is firmly held upon the standard or supporting shaft 7 by means of a retaining bolt 16 which retaining bolt 16 passes through a retaining washer 17 as shown in Fig. 2 of the drawings. It should be understood that the bearing collar 9 is threaded upon the upper end 8 of the

60

75

90

95

100

105

110

supporting shaft 7 and is adapted to be held stationary after once placed in a set position and permitting the hub portion 12 of the band wheel to freely and readily rotate around the bearing collar 9.

The hub portion 12 of the band wheel is provided with a depending collar 18, which depending collar 18 is provided with a laterally extending flange 19 through which flange 19 extends the securing bolts 20, the securing bolts 20 extending through the securing disk 21 and being anchored at their lower ends in engagement with the rotating collar 22. This rotating collar 22 is adapted 10 to rotate freely within the socket portion 23 formed in the base plate 2 as shown clearly in Fig. 2 of the drawings and this socket portion 23 is adapted to be filled with oil for the purpose of facilitating the free rotation 15 of the collar 22 therein. The collar 22 is provided with a laterally extending flange 24 which laterally extending flange 24 overhangs the bearing rings 25 which rings are supported upon the base plate 2.

25 The securing disk 21 carries a hitching ring 26 which hitching ring is provided with a circumferentially extending groove 27 formed upon the under face thereof for receiving the upwardly extending rib 28 carried by the securing disk 21. The hitching ring 26 is also provided with a depending flange 29 for fitting into the socket 30 formed in the securing ring 21. This hitching ring 26 is held upon the securing ring 21 30 by means of overhanging angle plates 31. The overhanging angle plates 31 are secured to the securing ring 21 and extend over the edge of the hitching ring 26 as shown in detail in Fig. 13, the plates 31 being firmly 35 secured for engagement with the disk 21 by means of securing bolts 32. As shown clearly in Fig. 5 of the drawings it will be seen that the securing disk 21 is made as light as possible for producing a strong and 40 effective structure for providing a plurality of spokes 33 upon the disk. It should be further understood that this securing disk 21 is eccentrically mounted upon its pivot point as shown in Fig. 5 of the drawing and 45 with the hitching ring 26 is adapted to freely rotate upon the securing ring 21 in order to produce a reciprocating movement upon a securing hitch attached to the hitching ring 26 when the disk 21 is rotated due 50 to the fact that the disk 21 is of course anchored in engagement with the band wheel 13 through the hub portion 12. A plurality of hitching apertures 34 are arranged around the periphery of the hitching ring 55 26 for the purpose of permitting any suitable or desired hitch to be secured to the periphery of the disk 26 at any angle radiating from the central axis of the apparatus.

The hub portion 12 is provided with a 60 plurality of radiating sockets 35 upon the

underface thereof within which sockets 35 fit the radiating spokes 36 of the band wheel 13. These spokes 36 are secured at their outer ends to the segmental sockets 38 carried between the spaced angle plates 37 of 70 the rim 39 of the band wheel. These segmental clamping plates 37 are firmly held in engagement with the angle plates 38 of the rim portion 39 by means of suitable bolts 40, the angle plates 38 being in turn secured to 75 the rim 39 by means of suitable securing bolts 41.

A trammel plate is supported directly above the hub portion 12 and this trammel plate comprises a body 42 which body 42 is 80 provided with a plurality of radiating arms 43. These radiating arms 43 are provided with longitudinally extending channels 44 within which channels 44 are adapted to travel the shoes 45. The trammel plate 42 85 is of course anchored to the hub 12 of the band wheel by means of securing bolts 46 shown in Fig. 3 of the drawings. The arms 43 of the trammel plate are provided with laterally extending ears 47 to which ears 47 90 are connected the angle braces 48. The braces act as a preventive of possible broken rods 75 dropping down and catching on yoke-bolts 48' of casting 12. Each of the shoes 45 comprises an elongated central bar 95 49 which elongated central bar 49 carries a plurality of transversely extending pins 50 having their ends seated within the sockets 51 carried by the side rails 52 of the shoes. These side rails 52 are adapted to constitute 100 a bearing face against the side walls 53 of the track-ways 44 and the side plates 52 are firmly held against the sides of the elongated bar 49 by means of the end heads 54. These end heads 54 are provided with a pair 105 of dove-tailed side portions 55, which are adapted to fit over the dove-tailed ends 56 of the side rails 52 and assist in holding the side rails against spreading relation. Binding screws 57 pass through the heads 54 110 and engage the ends of the elongated bar 49 and firmly hold the heads in engagement with this elongated bar. Additional binding screws or locking screws 58 pass through the side rails 52 and assist in holding the 115 side rails 52 in engagement with the elongated bar 49. Each shoe is similarly constructed and it is thought unnecessary to go into a detailed description of each individual shoe. The elongated bar 49 of each shoe 120 carries a vertically extending cup portion 59 which is adapted to contain lubricant and an inverted cup portion 60 is adapted to fit in the cup portion 59 as shown in Fig. 2 of the drawing. A drain plug 61 is carried by 125 the cup portion 59 near the bottom thereof for the purpose of permitting lubricant to be drained therefrom when it is so desired. Vertically extending pins 62 extend through the cup portion 59 and also through the cup 130

63 of the inverted cup portions 60 for the purpose of receiving securing nuts 64 and thereby firmly holding the inverted cup portions 60 within the cup portions 59. The 5 inverted cup portions 60 are provided with integral top plates 65 which top plates 65 are provided with elongated apertures 66 formed in the sides thereof for the purpose of receiving the bolts 67 which secure the 10 plates 65 in engagement with the anchoring bars 68 of the top hitch ring 69. In this manner the shoes will be connected and secured to the reciprocating rod 70.

This reciprocating rod 70 passes under the 15 anchoring plates 68 and is seated within the socket portions 71 formed in the top hitch ring 69 being held thereon by means of the yoke bolts 72 as shown in Fig. 2 of the drawing. Suitable apertures 73 and 74 are formed 20 in the top hitch disk 69 for receiving a hitch rod 75.

The outer end of this reciprocating rod 70 carries a roller bearing 76 which roller bearing 76 is adapted to travel upon the side 25 rails 77 of the outer support 78. This outer support 78 comprises a vertically extending standard having an enlarged head 79 to which head 79 is secured the rails or tracks 77. The bearing 76 is provided with a socket 30 portion 80 within which socket portion 80 fits the cup portion 81, the cup portion 81 being anchored in engagement with the reciprocating rod 70 by means of the yoke rods 82. This cup portion 81 is also firmly 35 held in engagement with the roller bearing 76 by means of the securing bolt 83. A hitching cap 84 is secured to the outer end of this rod 70 and this cap 84 is in turn connected to a suitable link 85 to permit the reciprocating rod 70 to be hitched or secured to any 40 suitable or convenient means, whereby power may be derived from the band wheel 13 through the medium of the reciprocating rod 70. The cap 84 is firmly clamped around the 45 outer end of the rod 70 by means of the clamping bolts 86 and the hitch rod 85 is pivotally connected to this cap 84 by means of a pivot bolt 87.

By referring to Figs. 3 and 8 it will be 50 seen that the arms 43 which are provided with the track ways or sockets 44 are also provided with suitable sockets 88 within which sockets fit the longitudinally extending retaining plates 89. The retaining plates 55 89 overhang the side rails 52 of the shoes 45 and thereby retain the shoes against accidental displacement from the track ways 44. These plates 89 are firmly held upon the arms 43 by means of suitable securing bolts 90.

60 What is claimed is:

1. In a mechanism of the class described the combination with a base, a base plate, said base plate provided with a vertically extending standard, of a bearing collar threaded upon said standard, said bearing collar

provided with inwardly inclined edges, a hub plate supported by said bearing collar, a retaining disk carried by said standard and overhanging said collar, and a securing bolt passing through said disk and standard for 70 permanently locking said disk upon said standard and preventing said bearing collar from being accidentally unthreaded from said standard.

2. In a mechanism of the class described 75 the combination with a base, a band wheel carried by said base and rotatably mounted thereon, means connected to said band wheel for facilitating the attachment of a hitch thereto and imparting reciprocating movement to, a hitch secured thereto as said band wheel rotates, a trammel plate carried by the top of said band wheel and comprising a plurality of radiating arms, each arm provided with a track way, a reciprocating rod, shoes 80 carried by said reciprocating rod, said shoes working in said channels, means for preventing the removal of said shoes from said channels, and means connected to said reciprocating rod for facilitating the attachment 85 of a hitch thereto.

3. In a device of the class described the combination with a base, a band wheel carried thereby, of a trammel plate secured to said band wheel and comprising a plurality of 95 radiating arms each radiating arm provided with a track way, a reciprocating rod, a frame carried by said reciprocating rod and comprising a hitch ring, bridge bars connected to said hitching ring, depending shoes 100 supported upon said bridge bars and working within said track ways, and means carried by said trammel plate for preventing the accidental removal of said shoes from said trammel plate.

4. In a power machine of the class described the combination with a base, a band wheel, of a trammel plate comprising a plurality of arms, said arms provided with channels formed therein, a reciprocating 110 rod, a frame carried by said rod, said frame comprising a hitching ring, bridge bars connected to said hitching ring, said bridge bars carrying a plurality of depending cup portions, shoes slidably mounted within said 115 arms of said trammel plate, each shoe provided with an upwardly extending cup portion for receiving the cup portions of said bridge bars, means for holding said cup portions in an assembled position, and means 120 for preventing the accidental removal of said shoe from said trammel plate.

5. In a power machine of the class described the combination with a base, a band wheel, of a trammel plate comprising a plurality of arms, said arms provided with channels formed therein, a reciprocating 125 rod, a frame carried by said rod, said frame comprising a hitching ring, bridge bars connected to said hitching ring, said bridge 130

- bars carrying a plurality of depending cup portions, shoes slidably mounted within said arms of said trammel plate, each shoe provided with an upwardly extending cup portion for receiving the cup portions of said bridge bars, means for holding said cup portions in an assembled position, and means for permitting the adjustment of said cup portions carried by said bridge bars longitudinally upon said bridge bars.
6. In a power machine of the class described the combination with a band wheel, of a trammel plate carried thereby, a reciprocating rod, sliding shoes carried by said rod and adapted to work upon said trammel plate, each shoe comprising a cup portion, means engaging said cup portion for anchoring the same in engagement with said reciprocating rod, each shoe also provided with a longitudinally extending bar, side rails detachably secured to said longitudinally extending bar and adapted to constitute bearing means for said shoe upon said trammel
- plate, and means engaging the ends of said side rails for firmly holding the same in engagement with said longitudinally extending bar.
7. In a power machine of the class described the combination with a band wheel, of a trammel plate, said trammel plate provided with track ways formed thereon, shoes traveling within said track ways, each shoe comprising a longitudinally extending bar, each side rail provided with a notched end, a head secured to the ends of said longitudinally extending rail and connecting the notched ends of said side rails and assisting in holding said side rails in firm engagement with said bar, and binding screws passing through said side rails and engaging said longitudinally extending bar for firmly holding said rails in a binding engagement with said longitudinally extending bar.

In testimony whereof I hereunto affix my signature.

HERBERT H. ICE.
